UNITED STATES PATENT OFFICE.

JOSEPH R. FINNEY, OF PITTSBURG, PENNSYLVANIA.

IMPROVEMENT IN NAIL-PLATE FEEDERS.

Specification forming part of Letters Patent No. 148,200, dated March 3, 1874; application filed February 25, 1874.

To all whom it may concern:

Be it known that I, JOSEPH R. FINNEY, of Pittsburgh, in the county of Allegheny and State of Pennsylvania, have invented a certain new and useful Improvement in Feeding Apparatus for Nail-Cutting Machines; and I do hereby declare that the following is a full, clear, and exact description thereof, reference being had to the accompanying drawings and to the letters of reference marked thereon.

My invention relates to an automatic feeding device for nail-cutting machines; and consists in a plate-chamber and feeding-tongs, which are raised by an eccentric, and turned or rotated by means of a wheel on their inner end, and geared into a reciprocating rack, which is operated by means of a curved disk, the plates from which the nails are cut being fed to the nail-cutting machine through the feed-tongs by means of two feeding-racks operated by a pawl, ratchet-wheel, and a section-wheel, and two wheels provided with coiled springs, all being so combined, arranged, and operating with relation to each other that when one rack is feeding a plate into and through the feed-tongs, the other rack will travel back for the purpose of taking another plate to carry it forward into the feed-tongs.

To enable others skilled in the art to make and use my invention, I will proceed to describe more fully its construction and operation.

In the accompanying drawings, which form part of my specification, Figure 1 is a longitudinal and vertical section of my improvement in feeding device at line y of Fig. 2. Fig. 2 is a top view or plan of the same. Fig. 3 is a longitudinal section at line x of Fig. 2. Fig. 4 is a rear-end elevation of the same. Fig. 5 is a detailed view of the feeding-racks and wheels which gear into them.

In the accompanying drawings, A represents the frame of the machine, which may be constructed of wood or iron, preference being given to iron. B and C represent the two main driving-wheels. On the axle of the wheel B are two cams, e and f , and on the axle of the wheel C is secured a curved disk, D, the periphery of which diverges from the right and left of the vertical line y^2 , shown in Fig. 4. h represents the plate-chamber of the machine,

the inner bottom of which is provided with a guide, g , and rests upon springs, as indicated at j . This bottom carries the nail-plates upward. k represents the feeding-tongs, a short distance from the point of which is secured a grooved sleeve, l , in which is placed a guide-yoke, i , pivoted to the side of the frame. This yoke and sleeve are used for the purpose of preventing any lateral motion, and yet allow the point of the tongs to have a vertical and rotating motion. On the inner end of the tongs is secured a wheel, m , provided with a transverse opening, n , communicating with the plate-opening in the tongs. The axle of the wheel m has its bearing in the cross-piece of the frame A. On the upper side of the frame are pivoted wheels r , u , and w , and above the wheel u is a ratchet-wheel, w' . The wheels r and w are provided with coil-springs s , for the purpose of causing them to operate the racks m' and n' , so that when the teeth of the wheel u pass out of gear with the teeth of the racks m' and n' , the racks will be carried back for the purpose of bringing forward from the plate-chamber h a fresh plate to the tongs. Two parts of the periphery of the wheel u are provided with gear-teeth, which mesh into the gear-teeth of the racks m' and n' , the teeth on one side of the wheel u being so arranged that, prior to passing out of gear with the rack n' , the teeth on the other side of the wheel will come into gear with the teeth of the rack m' . The racks m' and n' are provided with guide-rods s' and t' , the inner end of guide-rod t being used for the purpose of forcing the plates into the feeding-tongs. On the upper end of the lever o' , which is pivoted at x' , is a pawl, y' , the hooked end of which catches the teeth of the wheel w' , and thereby rotates it, the pawl y' preventing it from turning backward. e is an eccentric placed on the shaft u' of the driving-wheel B, and is used for raising the point of the feeding-tongs prior to their being turned, through the medium of the disk D, rack l' , and wheel m .

The operation of the hereinbefore-described feeding apparatus is as follows: The driving-wheel B is revolved through the medium of a pitman connected, in any suitable manner, to the cutting-jaw of the nail-cutting machine, as indicated at B', in Fig. 2. The revolving of

the wheel B will revolve the wheel C and disk D, and the revolving of the disk D will impart to the rack l' a reciprocating motion, thereby rotating the wheel m , which will rotate the feeding-tongs k . Prior to the tongs being rotated, the eccentric e elevates their point by coming in contact with the drum C'. The eccentric f , on the shaft u' of the driving-wheel B, imparts to the lever o' a reciprocating motion, which imparts a similar motion to the pawl y' , which rotates the wheel w' , on the axle of which is secured the wheel u , which is rotated with the wheel w' , and operates the racks m' and n' , which turn the wheels w and r , thereby winding up the springs s placed in them, the springs being attached to the side of the recess in the wheels and to their axes, so that when the wheel u passes out of gear with the rack n' the wheel w will carry the rack forward toward the tongs k , carrying a plate from the plate-chamber and forcing it into the tongs through the transverse opening u in the wheel m . At this point the wheel u passes out of gear with the rack m' , and the wheel r will carry the rack m' forward, so that the inner end of the guide-rod t' will force the plate through the tongs which were brought forward by the part x' of the rack n' , the rack m' having again become geared with the wheel u . The plate from which the nails are cut is moved forward in the tongs to the nail-cutting ma-

chine a distance equal to the throw of a single tooth of the rack m' —that is to say, the number and size of the nails made from each plate will depend on the number and size of the teeth on the rack m' and the number of teeth on the wheel u for operating it.

The plates from which the nails are cut are placed in the plate-chamber h , and the springs j force upward the bottom upon which they rest, always keeping a plate in the proper plane for being carried forward by the rack n' , as hereinbefore described.

Having thus described my improvements, what I claim as of my invention is—

1. The tongs k , lifted and rotated by the eccentric e , wheel m , rack v , and disk D, in combination with the mechanism hereinbefore described for feeding the nail-plate forward to the cutters, as and for the purpose set forth.

2. In combination with the tongs k , the plate-chamber h , the racks m' and n' , wheels r and w , section-wheel u and ratchet-wheel w' , pawl y' and stop-pawl r' , lever o' , and eccentric f , all constructed, arranged, and operating with relation to each other, substantially as herein described, and for the purpose set forth.

J. R. FINNEY.
